BURIAL APPARATUS

Wilbert W. Haase, Forest Park, Ill., assignor to
 Wilbert Manufacturers Association, Forest
 Park, Ill., a corporation of Illinois

Application September 15, 1945, Serial No. 616,627

10 Claims. (Cl. 27—32)

1

This invention relates to a concrete burial vault handling apparatus.

A concrete burial vault of the character with which the present apparatus may be employed is illustrated in and forms the subject matter of my copending applications, Serial No. 616,628 filed on Sept. 15, 1945, and Serial No. 703,645 filed on Oct. 16, 1946.

An object of the present invention is to provide a novel apparatus for assembling and lowering into the grave opening the parts of a concrete burial vault embodying a so-called air seal and embodying the construction disclosed and claimed in my aforesaid copending application, Serial No. 703,645.

Other and further objects of the present invention will be apparent from the following description and claims and are illustrated in the accompanying drawings which, by way of illustration, show preferred embodiments and the principles thereof and what I now consider to be the best mode in which I have contemplated applying those principles. Other embodiments of the invention embodying the same or equivalent principles may be used and structural changes may be made as desired by those skilled in the art without departing from the present invention and the purview of the appended claims.

In the drawings,

Fig. 1 is a plan view showing a preferred form of the new concrete burial vault assembling and lowering apparatus arranged in position of use at a grave opening;

Fig. 2 is a view on line 2—2 in Fig. 1, partly in section and partly in elevation showing the parts of the new burial vault assembling and lowering apparatus in the position which they assume when the casket has been lowered onto the casket-supporting base and prior to the operation of raising the base with the casket thereon into assembled relationship with the dome of the burial vault;

Fig. 3 is a view partly in section and partly in elevation showing the new burial vault assembling and lowering apparatus in the position in which the parts are disposed when the casket-supporting base and dome-shaped cover of the concrete burial vault have been assembled with the casket disposed therein and prior to raising the assembled vault to remove the wheels and wheel-bearing shafts from their bearing sockets in the end walls of the dome of the vault; and prior to lowering the vault and casket into the grave opening;

Fig. 4 is a fragmentary detail view showing part

2

of the guide rail construction for guiding the dome or dome-shaped cover of the burial vault on its supporting and guide wheels from a point at one side of the grave opening into position above the grave opening and showing one of the guide rollers for guiding the flexible vault-lowering members during use thereof;

Fig. 5 is a top plan view of the parts shown in Fig. 4, the gate being shown in open position; and

Fig. 6 is a sectional view on line 6—6 in Fig. 4.

The new concrete burial vault assembling and lowering apparatus is shown as being employed in connection with an air seal concrete burial vault, such as generally indicated at 10, and which 15 comprises a dome or dome-shaped cover 11 and a casket-supporting base 12 having a marginal edge portion 13 which provides a supporting frame on which the vault 10 with the casket 38 therein is adapted to rest when lowered into a 20 grave opening as 21.

A concrete burial vault, such as shown in the drawings, is illustrated in and forms the subject matter of my aforesaid copending application, Serial No. 703,645, and comprises an outer concrete wall 15 which is integrally bonded to an inner liner 16 of asphalt. The casket-supporting base 12 embodies a raised porous center portion 17 and an angularly extending wall 39 which interconnects the marginal edge portion 13 and the raised porous center 17 which is preferably made of cinder concrete or other suitable material. As shown in Fig. 3, the marginal edge portion 13 and the interconnecting wall 39 are composed of a lower and outer layer of non-porous concrete integrally bonded to an upper and inner layer of asphalt 40.

The dome or dome-shaped cover 11 of the vault 10 is provided with a pair of flanged guide wheels 18 at each end thereof, and these guide wheels are mounted on trunnions or wheel-bearing shafts 19 which are detachably inserted into suitable bearing openings 20 formed integrally in the end walls of the dome or dome-shaped cover 11 during the operation of molding said dome or dome-shaped cover 11.

The new concrete burial vault assembling and lowering apparatus is shown mounted in position at a grave opening 21, and comprises four upright corner posts or pedestals 22, each of 50 which is provided with a supporting base as 23. At least one pedestal 22 at each end of the grave opening contains a gear mechanism and other apparatus for controlling the operation of a rotatable shaft 24 one of which is rotatably journaled in each pair of the members 22 at each

end of the grave opening. Each of the shafts may be either electrically or manually controlled by a suitable control apparatus associated with one corner post 22 at each end of the grave opening and such a control apparatus may be that shown in the United States Patent No. 2,112,286 and embodies a control or crank handle 25 upon which a control crank may be mounted for controlling the operation of each shaft 24 and the raising and lowering of the flexible vault supporting members or straps 26. Thus, by reference to the drawings, it will be noted that the new vault assembling and lowering apparatus includes a pair of flexible vault supporting and lowering members or straps 26, and that the end portion of each of these flexible members or straps 26 is attached to and is wound upon a flanged guide spool 27' two of which are mounted upon each of the shafts 24.

The guide rollers 18 on the dome or dome-shaped cover 11 of the concrete burial vault 10 are adapted to travel over guide rails 27 which are substantially L-shaped in cross section, and each of which embodies an upright or vertical extending portion 28 and a horizontally extending base flange 29. The inner wall of each corner post or pedestal 22 is cut away or notched somewhat, as at 41, to enable the flanged guide rollers 18 to pass readily thereby and each of said inner walls of the corner posts or pedestals 22 is cut away or notched at its lower end, as at 42, for the reception of the outer edge portion of one of the rail bases 29 which rest on the supporting plates 23.

As shown in the drawings, one of these guide rails 27 is mounted at each end of the grave opening 21 and extends along the ends thereof and to a distance at one side of the grave opening, somewhat wider than the grave opening 21 itself, as best shown in Fig. 1. Each of the flexible vault lowering and raising members or straps 26 is guided over a guide roller 30, and these guide rollers 30 are rotatably journaled in bearing sockets 31 which are attached, in any suitable manner, as by welding, to the bases 29 of the guide rails 27 (Fig. 6).

As shown in Figs. 4, 5, and 6, the vertically extending portions 28 of each of the guide rails 27 is interrupted at two points by providing a cut-out portion 32 therein adjacent each of the guide rollers 30. Thus, as shown in Figs. 4 and 6, each of these cut-out portions 32 is substantially coextensive in length with one of the guide rollers 30 and is generally V-shaped in side elevation for a reason which will be made apparent presently.

Each of the guide rails 27 has a gate member 33 pivotally mounted thereon, as at 34, adjacent each cut-out portion 32, and each of these gates 33 is adapted to span one of the cutout portions or notches 32 in one of the guide rails 27. The front and rear edges 35 and 36 of each of the gates 33 extend angularly, as indicated at 35 and 36 in Fig. 4, and each gate 33 is provided with a pair of resilient latch arms 37 which are adapted to embrace the adjacent upright portion 28 of the guide rail 27 when the gate 33 is in closed position, as in full lines, Fig. 4, and as in Figs. 5 and 6.

In the practice of the present invention the hinged gates 33 are pivoted into fully open position, and in which the upper edges thereof will rest on the upper edges of the vertical rail flanges 28. The casket-supporting base 12 of the air seal burial vault 10 may then be mounted upon the flexible members or straps 26 and lowered or

suspended partially into the grave opening 21, as indicated in Fig. 2. During this operation the flexible members or straps 26 pass through the notches or cut-out portions 32 in the rails 27—28—29 and work over the guide rollers 30. A suitable casket-lowering device (not shown) may then be removably mounted on the four corner pedestals 22, in a manner well understood in the art, and during the committal or burial service 10 the casket may be lowered partially into the grave opening so as to rest upon the casket-supporting base 12 of the burial vault 10.

After the committal or burial service, the gates 33 may be closed and the dome 11 of the casket 10 may be brought into position adjacent the grave opening 21 and the guide rollers 18 thereon placed on the guide rails 27—28—29 (as in dotted lines, Fig. 1). The dome 11 may then be rolled along the guide rails 27 into a position above the grave opening 21, as in full lines, Fig. 1, the hinged gates 33 being then closed. The gates 33 may then again be opened and the base 12 of the burial vault with the casket 38 thereon, raised up to the mouth of the grave opening, by means of the flexible members 26, and the raising and lowering apparatus 22—24—25 associated therewith.

The vault raising and lowering apparatus 22, 24, 25 may then be operated by the controls 25 to raise the casket-supporting base 12 of the burial vault 10 with the casket 38 thereon up to the mouth of the grave opening 21 and so as to bring the marginal supporting edge portion 13 of the base 12 into engagement with the lower end portions 14 of the side and end walls of the dome or dome-shaped cover 11 of the vault 10. This effects an air and watertight seal between the asphalt inner liner 16 of the dome 11 and the asphalt inner liner 40 on the walls 13 and 39 of the base 12.

After the dome 11 and the casket-supporting base 12 of the vault 10 have thus been brought into sealing engagement with each other, with the casket 38 disposed therebetween, the thus assembled burial vault 10 with the casket 38 therein, may then be raised slightly so as to lift the guide rollers 18 off the guide rails 27, whereupon the guide rollers 18 and attached supporting shafts or trunnions may be detached from the vault 10 by slipping the wheel-bearing shafts 19 out of their bearing sockets 20 in the lower wall portions 14 of the vault dome 11. The thus assembled vault with the casket 38 therein but with the guide rollers 18 detached therefrom may then be lowered into the grave opening by manipulating the raising and lowering apparatus 22—24—25, and when thus lowered into the grave opening 21, the assembled burial vault 10 provides an air seal concrete burial vault having certain desirable advantages and characteristics which are pointed out in my aforesaid copending application, Serial No. 703,645.

It will thus be seen from the foregoing description, considered in conjunction with the accompanying drawings, that the present invention provides a novel apparatus for moving the cover dome and the casket-supporting base of a concrete air seal burial vault into assembled position and for lowering the same with a casket therein into position in a grave opening, and thus has the desirable advantages and characteristics, and accomplishes its intended objects, including those hereinbefore pointed out and others which are inherent in the invention.

I claim:

1. An apparatus for assembling the dome and the casket-supporting base of an air seal concrete burial vault and for lowering the assembled vault with a casket therein into a grave opening, said dome having flanged guide rollers detachably mounted thereon at the corners thereof: said apparatus comprising a pair of parallel guide rails adapted to guide the said flanged guide rollers carried by the said dome during movement thereover and each of said guide rails including a portion having an interruption therein adapted to be arranged at one end of a grave opening and each of said guide rails having a portion continuous with one of said first-named portions and adapted to extend laterally to one side of the said grave opening at the end thereof so as to enable the said dome to be moved over the said guide rails upon the said flanged guide rollers from a point at one side of a grave opening to a point above the said grave opening, means including a pair of horizontally extending rotatably mounted shafts adapted to be arranged in parallel relationship at opposite ends of said grave opening, means for rotatably supporting said shafts, a pair of flexible members extending between said shafts and windable onto and off said shafts and adapted to extend into said grave opening through the said interruptions in the said guide rails so as to support the said casket-supporting base of said concrete burial vault thereon, guide rollers rotatably mounted on said guide rails for guiding the said flexible members during movement thereof through the said interruptions in the said guide rails, and means forming parts of the said guide rails and movable into and out of position to close and open the said interruptions therein.

2. An apparatus as defined in claim 1 in which each of said guide rails has a pair of the said interruptions formed therein in spaced relationship with each other and in which each of said guide rails has one of said second-named guide rollers rotatably mounted thereon adjacent one of the said interruptions and in which said second-named guide rollers guide the said flexible members through the said interruptions in said guide rails during movement of said flexible members.

3. An apparatus as defined in claim 1 in which each of said second-named guide rollers is substantially coextensive in length with the adjacent one of the said interruptions in the corresponding one of said guide rails.

4. An apparatus as defined in claim 1 in which each of said guide rails has a cut-out portion therein and in which each of said guide rails has one of said second-named guide rollers rotatably mounted thereon adjacent one of said cut-out portions and in which said second-named guide rollers guide the said flexible members through the said cut-out portions in said guide rails during movement of said flexible members, and in which each of said second-named guide rollers is substantially coextensive in length with the adjacent one of the said cut-out portions in the corresponding one of said guide rails, and in which each of said guide rails has a gate member hingedly mounted thereon at one end of the corresponding one of said cut-out portions and in which each of said gate members is adapted to span one of the said cut-out portions when in closed position so as to allow the said flanged guide rollers on said dome to pass

thereover and thus traverse the said cut-out portions in said guide rails.

5. An apparatus as defined in claim 1 in which each of said guide rails has a cut-out portion therein and in which each of said guide rails has one of said second-named guide rollers rotatably mounted thereon adjacent one of said cut-out portions and in which said second-named guide rollers guide the said flexible members through the said cut-out portions in said guide rails during movement of said flexible members, and in which each of said second-named guide rollers is substantially coextensive in length with the adjacent cut-out portion in the corresponding one of said guide rails, and in which each of said guide rails has a gate member hingedly mounted thereon at one end of the corresponding one of said cut-out portions and in which each of said gate members is adapted to span one of the said cut-out portions when in closed position so as to allow the said flanged guide rollers on said dome to pass thereover and thus traverse the said cut-out portions in said guide rails, and in which each of said gate members is adapted to be hingedly swung into open position during movement of said flexible members so as to enable the said flexible members to pass over the said second-named rollers and through the said cut-out portions in said guide rails.

30 6. An apparatus as defined in claim 1 in which each of said guide rails has a cut-out portion therein and in which each of said guide rails has one of said second-named guide rollers rotatably mounted thereon adjacent one of said cut-out portions and in which said second-named guide rollers guide said flexible members through the said cut-out portions in said guide rails during movement of said flexible members, and in which each of said second-named guide rollers is substantially coextensive in length with the adjacent cut-out portion in the corresponding one of said guide rails, and in which each of said guide rails has a gate member hingedly mounted thereon at one end of the corresponding one of said cut-out portions and in which each of said gate members is adapted to span one of the said cut-out portions when in closed position so as to allow the said flanged guide rollers on said dome to pass thereover and thus traverse the said cut-out portions in said guide rails, and in which each of said gate members is adapted to be hingedly swung into open position during movement of said flexible members so as to enable the said flexible members to pass over said second-named guide rollers and through the said cut-out portions in said guide rails, and in which each of said gate members has a latching device thereon adapted to latchingly engage one of said guide rails so as to releasably hold the said gate members in closed position.

7. A burial apparatus comprising a pair of substantially parallel guide rails each having a portion adapted to be arranged at one end of a grave opening substantially parallel to an end wall of said grave opening and each having a portion adapted to extend beyond one side of the grave opening so as to enable flanged guide rollers bearing a part of a concrete burial vault to be moved along said guide rails from a point at one side of a grave opening to a point above the grave opening, each of said guide rails having a pair of spaced cut-out openings formed in that portion thereof which is adapted to be arranged at the end of the grave opening and each of said cut-out openings being adapted to have a flexible mem-

ber of a burial vault lowering apparatus pass therethrough during movement of said flexible member, each of said guide rails having a gate member movably mounted thereon and each of said gate members being adapted to open and close one of said cut-out openings, and said gate members spanning the said cut-out openings in the said guide rails when in closed position, so as to enable the said flanged guide rollers on the said part of said concrete burial vault to traverse the said cut-out openings when the said gate members are in closed position.

18. A burial apparatus as defined in claim 7 in which each of said guide rails has a guide roller rotatably mounted thereon for guiding one of the said flexible members through the adjacent one of said cut-out openings when the corresponding one of said gate members is in open position.

19. A burial apparatus as defined in claim 7 in which each of said guide rails has a guide roller rotatably mounted thereon for guiding one of the said flexible members through the adjacent one of said cut-out openings when the corresponding one of said gate members is in open position, and in which the said cut-out portions are formed in the vertically extending flanges of said guide

rails and in which the said guide roller for said flexible members are rotatably mounted on the base flanges of the said guide rails.

10. A burial apparatus as defined in claim 7 in which each of said guide rails has a guide roller rotatably mounted thereon for guiding one of the said flexible members through the adjacent one of said cut-out openings when the corresponding one of said gate members is in open position, and in which each of said gate members has a latching device thereon and in which said latching devices are adapted to latchingly engage the said guide rails so as to releasably latch the said gate members in closed position.
